UNITED STATES PATENT OFFICE.

MILTON W. KELLEY, OF AUSTIN, TEXAS.

KNEE PAD.

Application filed March 8, 1927. Serial No. 173,695.

The device forming the subject matter of this application is a knee pad of the kind used by athletes, and the invention aims to provide a pad which will be light in weight, and retain a fixed position on the leg and not impede the athlete when he is running or jumping. Another object of the invention is to provide a pad of the sort described which will conform closely to the shape of the knee, allow free circulation of the blood, and afford ample protection.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in side elevation, a device constructed in accordance with the invention;

Figure 2 is an elevation wherein the structure is viewed at right angles to the showing of Figure 1;

Figure 3 is a section on the line 3—3 of Figure 2;

Figure 4 is a section on the line 4—4 of Figure 1.

The pad forming the subject matter of this application comprises a trough-shaped body 1 folded upon itself and stitched together along a longitudinal line 2 near its lower end to form a projecting knee cap cup 3 at the upper end of the body, the upper end of the body being folded upon itself and stitched together along a plurality of inwardly extended lines 4 to form a rearwardly inclined upper wall 5 for the cup 3. A flexible binder 6, preferably made of canvas or other textile material, encloses the edge of the wall 5 and is stitched or secured otherwise in place. A protecting disk 7, preferably made of pig skin, is stitched or secured otherwise to the knee cap cup 3 near to the central portion thereof. A reinforcing strip 8, which may be made of textile material, is extended transversely of the body 1 at the lower end thereof, and is

secured by stitching or otherwise. A reinforcing strip 9, which may be made of textile material, is extended transversely of the body intermediate the ends thereof, and is located immediately below the knee cap cup 3, to aid in holding the cup in shape. One end of a retaining strap 10 is secured to the body 1 and to the strip 9. The opposite end of the strap 10 has a reduced tongue 11 provided with a slit 12 adapted to receive a button 14 on the pad, to form a detachable connection with the pad: although any other fastening means than the slit 12 and the button 14 may be used if desired. Reinforcing pieces 15, preferably made of pig skin, are stitched or secured otherwise to the body 1, the reinforcing pieces 15 covering the ends of the binder 6 and covering the ends of the strips 8 and 9, one of the reinforcing pieces 15 covering also, the fixed end of the strap 10. The strap 10 is provided with spaced transverse ribs 3, preferably made of felt, like the body 1, the ribs being compressible enough to avoid discomfort to the wearer, and being stiff enough to prevent the strap 10 from indenting the leg of the wearer and cutting off circulation.

The device forming the subject matter of this application is simple in construction, but it will be found to be thoroughly adequate to withstand the severe use to which devices of the kind designed are put. The structure, moreover, will cause the wearer no appreciable discomfort, and may be readily attached and removed as occasion may demand.

What is claimed is:—

1. A knee pad comprising a trough-shaped body folded upon itself and stitched together along a longitudinal line near its lower end to form a projecting knee-cap cup at the upper end of the body, the upper end of the body being folded upon itself and stitched together along a plurality of inwardly extended lines to form a rearwardly inclined upper wall for the knee cap cup; and means for securing the pad on the knee of the wearer.

2. A knee pad comprising a trough-shaped body folded upon itself and stitched together along a longitudinal line near its lower end to form a projecting knee-cap cup at the upper end of the body, the upper end of the body being folded upon itself and stitched together along a plurality of inwardly extended lines to form a rearwardly

inclined upper wall for the knee-cap cup, a flexible binder enclosing the edge of the upper wall for the knee-cap cup, a protecting disk secured to the knee-cap cup near to the central portion thereof, and means for securing the pad to the knee of the wearer.

3. A knee pad comprising a body provided at its upper end with a knee-cap cup, a binding for the upper edge of the knee-cap cup, a reinforcing strip extended transversely of the body at the lower end thereof, a reinforcing strip extended transversely of the body intermediate the ends thereof and located

immediately below the knee-cap cup to aid in holding the cup in shape, a retaining strap having a fixed end secured to the body, means for detachably securing the opposite end of the strap to the body, and reinforcing pieces extended along the longitudinal edges of the body and covering the ends of the binding and the ends of the strips, one of the reinforcing pieces covering the fixed end of the strap.

In testimony that I claim the foregoing as my own, I have hereto affixed my signature.

MILTON W. KELLEY.
